GEORGE H. ZOUCK, OF ORANGE, NEW JERSEY, ASSIGNOR TO FRANKLIN RAILWAY SUPPLY COMPANY, OF NEW YORK, N. Y., A CORPORATION OF DELAWARE

LOCOMOTIVE BOOSTER CYLINDER COCK CONTROLLING MECHANISM

Application filed October 15, 1930. Serial No. 488,730.

This invention relates to locomotive booster motors and particularly to the controlling mechanism therefor, with especial reference to those portions of the controlling mechanism which have to do with the proper functioning of the booster cylinder cocks.

As is now well known in this art the cylinder cocks on the locomotive booster cylinders are controlled by means of a device which normally functions to hold them in open position for a short period of time after the booster is placed into operation, so that the cylinders may be cleared of condensation which has a tendency to accumulate in usually large quantities because of the necessarily exposed location of the booster, the length of the steam supply pipes, etc. A fluid actuated motor device has been provided which normally holds the cocks in open position, but which can be disabled or moved out of holding position by supplying the device with fluid pressure, generally air pressure taken from the air reservoir on the locomotive.

The air reaches this motor device through the usual booster controlling system and the delay in permitting the cocks to close has been provided for by means of a timing reservoir in the line which supplies the air to the motor device in question. The reservoir has been fed through a restricted orifice so that an appreciable time element intervenes before the reservoir fills with pressure and the cylinder cocks close.

Due to certain practical difficulties met with in operation the delay or time element intervening before the cylinder cocks close is sometimes of uncertain duration because, as wear occurs, for example, the operation tends to become somewhat less uniform, and a delay which is longer than necessary, while not especially harmful, is wasteful of steam.

With the foregoing in mind, the objects of the invention will be better understood and these may be said to include the provision of an improved cylinder cock controlling mechanism by means of which it is possible to insure positive closure of the cylinder cocks within a reasonably fixed period of time; the provision of a mechanism of the

character described in which only a small portion of the fluid pressure system is fed through a restricted orifice so that the detrimental effect of leakage is reduced to a minimum; the provision of such a mechanism which is of greatly simplified construction and the parts of which can be more easily and cheaply manufactured and fitted; and the provision of mechanism of this kind by means of which a full and free flow of fluid may be delivered to the actuating device so that uniform and fully effective operation thereof may result without the necessity of exercising more than ordinary or customary care in manufacture and maintenance.

How the foregoing objects, together with any other objects which may appear hereinafter, or are incident to this invention, are attained is disclosed in a preferred form in the accompanying drawings, wherein—

Fig. 1 is a diagrammatical representation of a booster controlling system;

Fig. 2 is a longitudinal section through a valve mechanism employed in my invention; and

Fig. 3 is an enlarged sectional view of the cylinder cock operating mechanism.

The booster controlling system as a whole is now well understood in this art and most of the parts, therefore, in Fig. 1 have not been illustrated in detail, since it is believed to be unnecessary in connection with the present disclosure. However, reference may be had, if desired, to the patent to Lye and Ferrier, No. 1,727,125, issued September 3, 1929, which illustrates a booster controlling mechanism including cylinder cock operating mechanism substantially the same as that employed in the present arrangement. Reference may also be had to Peters Reissue Patent No. 16,483, issued November 23, 1926 and to Peters Patent No. 1,697,691, issued Jan. 1, 1929, which disclose various features of booster controlling mechanisms similar to the one herein made use of.

Briefly described, the drawings, illustrate the customary fluid pressure actuated booster controlling mechanism in which the pressure utilized is air pressure taken from the reservoir (not shown) through the pipe 3 which

leads to the well known reverse lever pilot valve construction 4 which is under the control of the locomotive reverse lever 5.

In certain predetermined positions, 5 through the medium of the bell crank lever 6, the reverse lever 5 will depress the plunger 7 in the reverse lever pilot valve 4 so that the air pressure coming in through the pipe 3 can continue on through the pipe 8 to the booster 9.

If it is desired to idle the booster prior to entraining it as a driving factor in the manner well understood in the art, the handle 10 can be turned to establish communication 15 between the pipe 3 and the pipe 11, the latter pipe leading to the preliminary throttle valve 12. When this preliminary throttle valve is opened steam will be admitted through the pipe 13 to the booster steam 20 supply line 14. The steam so admitted is restricted in amount by means of the choke 15 so that the booster will be operated at comparatively slow speeds or "idled" until such time as it is desired to throw it into 25 operation.

The air pressure reaching the booster 9 through the pipe 8 will first effect entrainment by moving the idler gear 16 into mesh with the gear 17 fixed on the axle 18, the 30 idler gear 16, of course, being at all times in mesh with the driving pinion 19 which is rotated by the booster cylinders 20. After entrainment is effected the air will continue on through the pipe 21 to the customary pilot 35 valve 22, as well as to the main throttle valve 23 located in the booster steam supply pipe 14. When the main throttle valve 23 is opened steam will be delivered to the booster in operating quantities, the pipe 14 being 40 connected either to the main steam pipes of the locomotive (not shown) or to some other suitable source of supply on the locomotive boiler.

As soon as sufficient pressure is developed 45 in the pipe 14 the pilot valve 22 will function to permit the air coming in through the pipe 21 to pass on through the pipe 24 which leads to the cylinder cock controlling mechanism with which we are particularly concerned in 50 the present application.

In the pipe 24 is located a valve mechanism indicated as a whole by the reference character 25 (see particularly Fig. 2). This valve includes the movable closure member 55 26 which is held against the valve seat 27 by means of the spring 28. A stem 29 extends outwardly away from the member 26 and has its remote end secured to a diaphragm 30 adapted to be acted upon by fluid 60 pressure in the timing reservoir 31.

In the absence of pressure in the reservoir 31 the diaphragm 30 will be upwardly bowed as shown in Fig. 2 and the valve 26 will be tightly closed so as to prevent the flow of 65 pressure through the pipe 24.

The timing reservoir is connected to the pipe 24 by means of a pipe 32 in which is located a restricted orifice 33 so that an appreciable time element will be involved in the building up of a predetermined pressure 70 in the reservoir 31. This time element can be varied, of course, by changing the size of the orifice 33. When the predetermined pressure is reached, the diaphragm 30 will be depressed and the valve 26 lifted from its seat so that the air pressure can flow through the pipe 24 in the direction of the arrows 75 appearing in Fig. 2.

This air pressure will be delivered to the cylinder cock controlling mechanism indicated as a whole by the reference character 80 34, the construction and operation of which are as follows:

The booster cylinders 20 are provided with cylinder cocks 36, the ball valves 37 of which are normally held away from their seats by means of the plunger rods 38 which are coupled to the operating spider 39 normally subject to the pressure of the spring 40 through the medium of the piston 41 and rod 42. 85 The spring 40 acting against the piston 41 forces it to the right and moves with it the member 39 which, in turn, actuates the rods 38 to hold the balls 37 away from their seats. In this way the cylinder cocks are always 90 normally in open position. Whenever the booster is thrown into operation or begins to function, the cylinder cocks will always be found in open position so that any water of condensation may be driven out. In this way 95 there is no danger of blowing out the cylinder heads of the booster.

After the desired pressure has been created in the reservoir 31, the air coming in through the pipe 24 will move the piston 41 and its 100 operating rod 42 to the left so that the spider 39 will withdraw or retract the rods 38 from the position in which they hold the balls 37 away from their seats. The cylinder cocks 105 will then close under the influence of the pressure in the booster cylinders in the manner well understood in this art.

It will, therefore, be seen that I have provided an arrangement which is always positive in its action and the operation of which 110 will in no way be affected by slight leakage around the operating piston 41 or at any other point in the mechanism. Heretofore the amount of air which it was possible to pass through the restricted orifice 33 was frequently dissipated by leakage for a considerable period of time before a sufficient pressure was built up in the timing reservoir to effect operation of the piston 41.

But with my improvements this difficulty 115 does not arise because once the valve 26 is opened the full amount of the pressure available is immediately delivered to the face of the piston 41 so that it will be moved promptly to the left in order to permit the ball valves 120

37 to seat and thereby close the cylinder cocks. Operating in this way slight leakages will have substantially no effect upon the amount of delay or time involved in closing the cylinder cocks.

5 Furthermore, with my improvements it is not necessary to fit the operating piston 41 with piston rings because a slight leakage of air will not materially affect prompt operation thereof in view of the full and free flow of air which is supplied through the pipe 24 just as soon as the valve 26 is opened.

10 What I claim is:—

15 1. The combination of a locomotive booster motor, a cylinder cock, fluid pressure actuated means for controlling said cock, a fluid supply line, a timing reservoir connected to said line, a valve normally closing the fluid pressure supply line to the cock, and means for opening said valve when the pressure in the reservoir builds up to a predetermined point.

20 2. The combination of a locomotive booster motor, a cylinder cock, fluid pressure actuated means for controlling said cock, a fluid supply line, a timing reservoir connected to said line, a restricted orifice in said reservoir connection, a valve normally closing the fluid pressure supply line to the cock, and means for opening said valve when the pressure in the reservoir builds up to a predetermined point.

25 3. A controlling mechanism for a locomotive booster cylinder cock characterized by the fact that closure of the cock is under the control of a fluid actuated motor device the fluid pressure supply line for which is normally closed but which will be opened upon the accumulation of a predetermined fluid 30 pressure in a timing reservoir connected to said supply line.

40 4. The combination of a locomotive booster motor, a cylinder cock, fluid pressure actuated means for controlling said cock, a fluid supply line, a valve normally closing said line, a fluid actuated motor device for opening said valve, said device being connected to said line, and means for delaying the supply of effective operating pressure through 45 said line to said device.

50 5. In a timing device for controlling the closure of a booster cylinder cock, the combination of a pipeline, a reservoir, a restricted opening leading to the reservoir, a pipeline 55 by-passing the reservoir and a valve communicating with the reservoir, said valve normally shutting off the by-pass but operable upon accumulation of a pre-determined pressure in the reservoir to permit full flow 60 through the by-pass.

In testimony whereof I have hereunto signed my name.

GEORGE H. ZOUCK.
